UNITED STATES PATENT OFFICE

LOUIS B. EHRLICH, OF TOLEDO, OHIO, ASSIGNOR TO THE ELECTRIC AUTO-LITE COMPANY, OF TOLEDO, OHIO, A CORPORATION OF OHIO

STARTING MOTOR SWITCH

Original application filed June 11, 1925, Serial No. 36,467, now Patent No. 1,839,916, dated January 5, 1932.
Divided and this application filed September 20, 1928. Serial No. 307,191.

This invention relates to controlling means for starting motor switches, and is a division of my application for "Starting motor switches", Serial Number 36,467, filed on 5 June 11, 1925, which issued into Patent Number 1,839,916, January 5, 1932.

Switches for starting motors for automobile engines are usually arranged on the floor board of the body under the foot of the 10 driver, but where they have been mounted directly on the motor the construction was such that it was still necessary to connect the switch terminal with the motor terminal by a cable or the like. In accordance with this 15 part of my invention, the construction of my switch and its installation on the motor are simplified by using the motor terminal as one terminal of the switch and extending that terminal insulatedly through the motor frame 20 for connection inside the motor to the field or armature winding or both. The switch terminal forming the other terminal of the switch is carried insulatedly by the motor frame, but the switch and its installation 25 may be further simplified by providing a switch housing which is fastened to the motor frame and not only carries the switch terminal but extends over the motor terminal. Preferably one of said terminals, usually the 30 switch terminal, carries the conducting member or switch blade which extends into cooperative relation with the other terminal and is usually a spring metal plate adapted 35 to be pressed into contact with that terminal by means of an operating lever pivoted on the switch housing. This operating lever may be actuated by the driver by means of a pull wire or by a push rod extending to a 40 knob on the face of the dashboard of the automobile, and the operating lever is preferably so constructed and arranged as to be suitable for both means of operation upon being reversed in position on a pivot supported by the housing.

In the accompanying drawing illustrating the preferred embodiment of my switch, Fig. 1 shows, partly in elevation and partly in section, the switch operated by a pull wire; Fig. 2 is a similar view showing the switch 50 operated by a push rod with the operating

lever of the switch reversed for that purpose; Fig. 3 is a central longitudinal section on an enlarged scale of the switch of Fig. 1; and Figs. 4 and 5 are sections on lines 4—4 and 5—5, respectively, of Fig. 3.

The motor frame 1 which houses the armature and field coils (not shown), has a terminal passing through it and insulated from it, as shown in Fig. 3, a lead (not shown) to the armature or field winding, or both, being soldered or otherwise fastened inside the frame to the bottom of the terminal between the ears 2 of the clip 3. This motor terminal has a top contact formed by a copper nut 4 screwed on the shank 5 of the copper stud bolt and held from turning thereon by the lock washer 6. The switch terminal 7 extends through the pressed-up metal switch housing 8 and is insulated therefrom as shown. Outside the housing the cable connector 9 is secured to the terminal for connection of the battery lead 10 and inside the housing the conducting element or switch blade 11 of spring copper is fastened to this terminal so as to extend over the nut 4 of the motor terminal, the switch housing 8 being fastened to the motor frame at 12 and covering the motor terminal. Mounted on the pivot pin 13 which passes through ears 14 struck up from the housing, is an operating lever 15 carrying the rollers 16 of insulating material near its inner end and having a hole near its outer end.

Where a pull wire is used for operation, the operating lever is arranged as shown in Figs. 1 and 3, the pull wire consisting of a wire 17 passed through the hole in the operating lever 15 and secured by the adjustable connector 18. At the body frame member 19 the wire passes through a guide tube 20 which is held in place by the fitting 21 passing through the dashboard 22, the wire 17 being fastened to the rod 23 having a knob or handle 24 at its end for operation by the driver.

Where a push rod is used for operation, the operating lever 15 is arranged as shown in Fig. 2 in reverse position on the pivot pin 13 and the rod 25 with an elongated slot at 26 is connected thereto by a cotter pin 27 or the like. This rod passes through a tube 100

28 secured to the face of the dashboard 29 and has a knob 30 for operation by the driver.

It will now be obvious that to close the switch for supplying current from the battery or other source to the starting motor, the operator merely pulls the knob 24 of Fig. 1 or pushes the knob 30 of Fig. 2, to the limit of its motion, whereby the switch blade 11 is pressed by the rollers 16 into intimate contact with the top contact of the motor terminal and the circuit thereby completed from the battery or other source to the motor. As a result of the bend at 31 in the switch blade, there is a slight but sufficient wiping action of the blade on the motor terminal, particularly in the arrangement with the pull wire, sufficient to keep the contacting surfaces clean. Upon releasing the knob, the spring tension in the switch blade 11 restores the parts to their normal or open position shown in the drawing.

Having thus described my invention what I claim is:

1. In a motor switch, a pair of terminals; an element attached to one of said terminals; a reversible lever adapted to be pivotally mounted in either of two positions with respect to said element and adapted to move said element into engagement with said other terminal in one position when the end of said lever is pulled, and in the other position when the end of said lever is pushed.
2. In a motor switch, a pair of terminals, a casing enclosing one of said terminals and insulatingly supporting the other terminal; a flexible element for completing a circuit between said terminals; means for flexing said flexible element including a lever and anti-friction means connected with said lever and interposed between said casing and said flexible element, and means including a flexible wire for manipulating said flexible member to complete the circuit.

3. In combination, a switch comprising a housing; a resilient switch blade in said housing; means insulatingly supported on said housing and fixedly retaining said switch blade; means for flexing said switch blade comprising a lever journalled upon said housing, the tension of said blade normally holding said means into engagement with said housing; and means including a flexible wire for manipulating said lever from a position remote to said switch.

4. In combination, a switch comprising a housing; a resilient switch blade in said housing; means insulatingly supported on said housing and fixedly retaining said switch blade; said retaining means acting as a connecting terminal; means for flexing said switch blade comprising a lever journalled upon said housing; a roller journalled in one end of said lever and adapted for rolling engagement with said switch blade, the tension of said blade normally holding said roller

into engagement with said housing; and means including a flexible wire for manipulating said lever.

5. In a motor switch, a casing; a terminal carried by said casing and insulated therefrom, said terminal having a portion projecting exteriorly of said casing; a resilient member carried by said terminal; manipulating means mounted upon said casing including a lever, and antifriction means comprising a roller of insulating material journalled upon said lever for engagement with said resilient member; a manipulating means including a flexible wire for operating said lever from a position remote to said casing.

6. In a device of the character disclosed, in combination, a switch casing; a terminal supported thereon and insulated therefrom; a spring switch blade carried by said terminal; a lever pivotally secured to said casing; a shaft forming a pivotal support for said lever having a plurality of annular grooves; means for holding said shaft in position including portions of said casing adapted to project into said annular grooves; anti-friction rollers carried by said lever for cooperation with said switch blade; and manipulating means operatively connected to said lever.

7. In a device of the character described, in combination, a substantially rectangular switch housing having a wall provided with flat portions arranged in substantially different parallel planes; a circuit terminal supported on one of the flat portions of said housing wall and insulated therefrom; a spring switch blade carried by said terminal within said housing; a lever pivotally supported upon struck up projections formed on the other flat portion of said housing wall; a shaft forming a pivotal support for said lever, the struck up portion of said housing holding said shaft in position; and an anti-friction roller carried by said lever for cooperation with said switch blade, said lever having a manipulating portion projecting exteriorly of the walls of said housing.

8. In combination, a switch comprising a substantially rectangular sheet metal housing having a wall provided with flat portions located in substantially different parallel planes; a resilient switch blade within said housing; a terminal insulatingly supported on a flat portion of said housing wall for fixedly retaining one end of said switch blade; means for flexing said switch blade comprising a lever journalled upon the other flat portion of said housing wall; and an anti-friction means connected with said lever and interposed between said housing wall and said switch blade, said housing wall having an opening adapted to accommodate a portion of said lever projecting externally of said switch housing.

9. In combination, a switch comprising a substantially rectangular housing having

spaced parallel side walls and a connecting wall, said connecting wall having flat portions arranged on different planes; a resilient switch blade in said housing; means insulatingly carried by one of the flat portions of said housing wall for supporting said switch blade, said supporting means having a portion projecting exteriorly of said switch housing and acting as a circuit terminal for said switch blade; means for flexing said

switch blade comprising a lever journaled upon the other flat portion of said housing wall; a roller of insulating material journaled at one end of said lever and adapted for rolling engagement with said switch blade, said lever having a manipulating portion projecting exteriorly of said housing. 70

In testimony whereof, I affix my signature.
